(57) **CLAIM**

The ornamental design for a pneumatic compression trousers, as shown and described.

DESCRIPTION

Fig. 1.1: is a front view of a first embodiment of the pneumatic compression trousers according to the invention; Fig. 1.2: is a rear view of the pneumatic compression trousers of Fig. 1.1;

Fig. 1.3: is a side view from the left of the pneumatic compression trousers of Fig. 1.1;

Fig. 1.4: is a side view from the right of the pneumatic compression trousers of Fig. 1.1;

Fig. 1.5: is a perspective view of the pneumatic compression trousers of Fig. 1.1;

Fig. 2.1: is a side view from the right of a second embodiment of the pneumatic compression trousers according to the invention;

Fig. 2.2: is a front view of the pneumatic compression trousers of Fig. 2.1;

Fig. 2.3: is a side view from the left of the pneumatic compression trousers of Fig. 2.1;

Fig. 2.4: is a perspective view of the pneumatic compression trousers of Fig. 2.1;

Fig. 2.5: is a rear view of the pneumatic compression trousers of Fig. 2.1;

Fig. 3.1: is a side view from the right of a third embodiment of the pneumatic compression trousers according to the invention;

Fig. 3.2: is a rear view of the pneumatic compression trousers of Fig. 3.1;

Fig. 3.3: is a side view from the left of the pneumatic compression trousers of Fig. 3.1;

(Continued)

Fig. 3.4: is a front view of the pneumatic compression trousers of Fig. 3.1;

Fig. 3.5: is a perspective view of the pneumatic compression trousers of Fig. 3.1.

The broken lines in the drawings depict zipper teeth and stitching and form part of the claimed design.

1 Claim, 15 Drawing Sheets
